(57) **CLAIM**

The ornamental design for a handle for utensil, as shown and described.

DESCRIPTION

FIG. 1 is a bottom perspective view of the handle for utensil; FIG. 2 is a top perspective view of the handle for utensil; FIG. 3 is a bottom plan view of the handle for utensil; FIG. 4 is a front perspective view of the handle for utensil; FIG. 5 is a rear elevation view of the handle for utensil; FIG. 6 is a right, side elevation view of the handle for utensil;

FIG. 7 is a left, perspective view of the handle for utensil; FIG. 8 is a bottom perspective view of the handle for utensil; FIG. 9 is a top, front perspective view of the handle for utensil in use; and,

FIG. 10 is a bottom, front perspective view of the handle for utensil in use.

The fork illustrated in broken lines in the drawings forms no part of the claimed design and the hand illustrated in broken lines in FIGS. 9–10 is for the purpose of illustrating environmental matter and forms no part of the claimed design.

1 Claim, 5 Drawing Sheets
